SANITARY HAIR-CATCHING MANTLE

Frank Ferry, Bristol, Pa., assignor of one-half
to Elwood W. Bilger, Bristol, Pa.

Application April 6, 1939, Serial No. 266,308

5 Claims. (Cl. 2—50)

My present invention relates to a sanitary appliance for use in barber shops and elsewhere and to be worn by the customer while he is being barbeced.

5 A purpose of the invention is to provide a hair-catching mantle that will be simple and inexpensive; that will collect the falling hair, dandruff, burnt particles from hair singeing and the like in a hairway for delivery into a normally closed 10 receiver carried by the mantle; that will be comfortable to wear, leaving the customer's arms free, as for smoking, without disturbing the proper fit of the mantle; that will adjustably fit the customer's neck and be so low on the neck 15 as to be out of the way of the different barbecing operations, avoiding any need for removing or even for shifting the mantle throughout a succession of barbecing operations, as for example of hair-cutting, neck shaving, hair singeing and 20 dry shampooing; that will be easy to put on and take off; that will effectively protect the customer, the barber and the floor from falling hair and other particles; that will be impenetrable to falling hair and other particles, and that will be 25 very easy to clean, whether by means of boiling water, steam or antiseptic solutions.

A further purpose is to surround a flexible and wide collar with a relatively stiff hairway, with 30 front and rearward portions of the hairway connecting and preferably hinging together at the customer's shoulders, preferably near the front of the shoulders, sloping downwardly and outwardly from the line of hinging, out peripherally far enough to catch falling hair and down far 35 enough to be out of the way of the barber.

A further purpose is to provide the wide collar with a zipper front and a narrow neck band, and with a fresh strip of paper for each customer folded over the neck band and down between the 40 neck band and the customer's neck.

A further purpose is to discharge both the rearward and front hairway portions through a downward opening of the front portion into a 45 preferably cylindrical receiver located below and horizontally across the bottom and front of the mantle.

A further purpose is to carry the hair receiver 50 removably in a receiver housing having an upward opening into the hairway, the receiver having a longitudinal opening to register with the housing opening when the hairway is to be discharged into the receiver.

A further purpose is to open and close connection 55 between the hairway and the receiver by

turning the receiver in its housing, opening and closing the receiver by bringing the receiver opening respectively into registry with the housing opening and out of registry therewith.

A further purpose, when operating for example in a hospital, is to barber optionally a succession of customer patients before emptying the receiver, keeping the receiver closed when the mantle is being worn by customers and clearing the mantle into the receiver after taking it off each customer.

A further purpose is to use the housing of the hair receiver to hold out the front portion of the mantle.

A further purpose is to hold out the rear portion of the mantle rearwardly by the engagement of downward spurs oppositely adjacent the line of hinging of relatively stiff peripheral portions of the mantle, respectively to the front and rear, with a pair of opposing spurs at each shoulder.

A further purpose is to support the mantle from the customer's shoulders, with its frontwardly and rearwardly extending portions in a measure balancing one another, each tending to hold the other outward by engagements of downward spurs at the line of hinging between relatively stiff peripheral portions of the mantle.

A further purpose is to accommodate any customer's wish to smoke by presenting from the mantle a stub surface for use in putting out unconsumed cigaret stubs and a receiver for ashes and stubs.

Further purposes will appear in the specification and in the claims.

I have elected to show one only of the different forms of my invention, selecting a form however that is practical and efficient in operation and which well illustrates the principles involved.

In the drawing:

Figure 1 is a perspective view illustrating a desirable embodiment of the invention as worn by a customer.

Figure 2 is a top plan of the embodiment of Figure 1, nearly in position of use and without the customer.

Figure 3 is a side elevation showing the structure of Figure 1 on a customer.

Figure 4 is a fragmentary section of Figure 2, taken upon the line 2—2 thereof in the direction of the arrows.

Like numerals refer to like parts in all figures.

Describing in illustration and not in limitation and referring to the drawing:

In the illustration, a one-piece mantle extends

downwardly and outwardly from around the neck and presents an outwardly extended upwardly directed hairway to catch hair and other particles falling during barbering, and below the front of 5 the mantle carries a cylindrical pan or hair receiver, normally closed and removably mounted within a casing suitably integral with the mantle.

The mantle also presents a stub surface for use by customers who smoke while being barbered, to extinguish finished cigarettes, and with an adjacent recess for cigaret stubs and ashes.

The mantle comprises a wide collar 5, front and rear hairways 6 and 7 outside the collar, the casing 8 opening upwardly at 9 into the front 10 hairway, cigaret stubbing pad 10, cigaret and ash receiver recess 11 and a pair of front and rear downward spurs 12 and 13 at each shoulder and oppositely adjacent a line 14—14 of upward hinging between the front and rear portions of 15 the mantle.

The wide collar 5 is provided with a narrow neck band 15 having in front a Zipper closure 16 that in release is long enough for an easy passage of the mantle over the customer's head. The 20 closure 16, herein conventionally called a Zipper, is intended for any suitable closure adjustable at the customer's neck.

In use, a fresh strip of paper 17, shown in place in Figures 1 and 3, is intended to be applied to the neck band with each use of the mantle. This paper strip 17, new for each customer, folds down over the neck band 16, shielding the neck band from direct contact with the customer's neck.

The wide collar 5 is preferably of material readily flexible while the front and rear hairways into which the collar 5 outwardly merges are intended to be stiff enough to hold the mantle out from the customer at the hairways. In Figure 2 the dot-and-dash line 18 is intended to show approximately the outward indefinite end of the collar and the inward indefinite beginning of the hairways.

The front and rear hairways are thus in effect 45 structural members, inwardly merging at 18 with the collar and having upwardly directed rims 19 and 20 that function structurally to strengthen the hairways for holding out the mantle as well as forming the outside upward wall of the hairways.

The hairways connect together at the shoulders in such a way that the front hairway supports the rear hairway in its rearward extension, the flexible collar supporting the mantle as a whole 55 on the shoulders of the customers, each hairway wholly or partially balancing the other on the customer's shoulders.

While I may provide any suitable supporting connection between the front and rearward peripheral structural portions 19 and 20 of the mantle, I prefer to have this connection one that permits upward hinging at 14—14 of the rear portion of the mantle as well as one adapting the front hairway to support the rear hairway in its rearward extension.

An adaptation for the mantle to hinge upwardly is particularly desirable when the mantle is to be used in hospitals, as the front and rear portions of the mantle will there often need 70 to accommodate in their position special and unusual positions and conditions of different customer patients of the hospital.

In the illustration, the structural portions of the upturned rims 19 and 20 are intended to end 75 at or somewhat before the line of hinging 14—14,

but optional lap extensions 21 and 22 are shown lapping one another across the line of hinging to insure better against the escape from the mantle of fallen hair at the line of hinging.

The hinge may comprise merely the flexible 5 material of the collar, preferably reinforced with fabric or the like.

The downward spurs 12 and 13 from the adjacent ends of the front and rear hairways, in engaging one another support the hairways from 10 downward hinging beyond the position of normal use, yet permit the rear portion of the mantle to be turned upward to any desired position, either for more easy delivery of cut hair out of the rear into the front hairway or better 15 to accommodate the mantle to different positions of customer patients in a hospital or elsewhere. The spurs preferably are located outwardly beyond the customer's shoulders.

The cylindrical pan or hair receiver 23 intended to be normally carried removably within the casing 8 may be a light metal cylinder, closed at the ends and longitudinally open at 24. It is shown with a handle 25 by which it may be turned angularly in the casing 8 or may be taken 25 out of the casing for discharge of its load.

Figure 4 illustrates the intended normal position of the hair receiver 23, the receiver being closed from connection with the hairway in that the receiver presents a portion of its outside wall 30 under the opening 9 of the hairway.

Only after finishing barbering a customer will the barber usually open the hair receiver by suitably turning it in the casing until the receiver opening 24 registers with the opening 9 from the front hairway, the cut hair either before or after taking off the mantle from the customer being brushed into the hairways and thence forward to the opening 9 preferably before opening the receiver.

The receiver may be taken out and discharged after each customer or optionally may accumulate cut hair from a number of customers, and from this standpoint is particularly convenient when the mantle is used in barbing the inmates 45 of hospitals.

Many customers insist on smoking while being barbed and the provision of the stubbing pad 10 and ash receiver 11 with freedom to get easily to his own pockets without in anywise disturbing the haircatching mantle permits the customer to smoke at will without help from the barber, while hitherto the barber frequently has had to get and light the customer's cigaret, to put out and remove the finished cigaret while 55 the cigaret ashes have gone to the floor of the shop.

It will be seen that the front overbalances the rear of the mantle, with the low position of the front limited and usually determined by the contact of the customer with the casing 8.

I prefer to make the mantle of light waterproof material, smooth and impervious to the falling particles of cut hair so that the cut hair may be readily delivered from the mantle by 65 brushing from the collar into the hairways and from the hairways into the receiver opening 9, and so that the mantle may be sterilized quickly and easily as often as desired in hot water or steam or any suitable antiseptic solution.

One of many such materials is rubber suitably reinforced in the hairways and casing with fabric.

In view of my invention and disclosure variations and modifications will doubtless become 70 75 76

evident to others skilled in the art, to meet particular need or individual whim, and I claim all such in so far as they fall within the reasonable scope of the invention.

5 Having thus described my invention what I claim as new and desire to secure by Letters Patent is:

1. A hair catching mantle for use in barber shops and elsewhere, the mantle comprising a 10 flexible wide collar having a zipper front, front and rear hairways inwardly merging with the collar, outwardly turning upwardly for hair retention and hinged together on opposite sides of the collar, permitting upward tilting of the rear 15 hairway for more easy delivery out of the rear hairway into the front hairway.

2. A hair catching mantle for use in barber shops and elsewhere, the mantle comprising a wide and flexible collar to pass over the customer's head and thereafter to fit adjustably 20 the customer's neck, fairly stiff front and rear hairways, hinged together on opposite sides of the collar and inwardly merging into the collar, pairs of downward spurs oppositely adjacent the 25 hinge on opposite sides of the collar and limiting the downward hinging of the rear hairway, thereby to hold the rear hairway in rearward extension.

3. A hair catching mantle for use in barber 30 shops and elsewhere, the mantle comprising a flexible wide collar over the customer's shoulders and around his neck, fairly stiff front and rear hairways together surrounding and inwardly merging with the collar and outwardly turning 35 upwardly for hair retention, connections on opposite sides of the collar between the hairways merging the rear hairway into the front hairway and adapting the front hairway to support the rear hairway in a rearwardly extending 40 position and a receptacle for cut hair removably mounted under and across the front hairway

at the front and low portion thereof and adapted to open upwardly into the front hairway.

4. A hair catching mantle for use in barber 5 shops and elsewhere, the mantle comprising a flexible wide collar over the customer's shoulders and around his neck, fairly stiff front and rear hairways together surrounding and inwardly merging with the collar and outwardly turning 10 upwardly for hair retention, connections on opposite sides of the collar between the hairways merging the rear hairway into the front hairway and adapting the front hairway to support the rear hairway in a rearwardly extending position and a casing under and across the front hairway and having an opening upwardly into 15 the front hairway and a receptacle removably mounted in the casing, the receptacle in one position opening upwardly into the casing opening and in another position closing the casing 20 opening.

5. A hair catching mantle for use in barber 25 shops and elsewhere, the mantle comprising a flexible wide collar over the customer's shoulders and around his neck, fairly stiff front and rear hairways together surrounding and inwardly merging with the collar and outwardly turning 30 upwardly for hair retention, connections on opposite sides of the collar between the hairways merging the rear hairway into the front hairway and adapting the front hairway to support 35 the rear hairway in a rearwardly extending position, a cylindrical casing under and across the front hairway having a longitudinal upward opening into the front hairway, a cylindrical receptacle within the casing and having a longitudinal opening in one position of the receptacle 40 registering with the casing opening for hair delivery into the receptacle from the front hairway and the receptacle in another angular position closing the casing opening by presenting the cylinder wall across the opening.

FRANK FERRY.
